UNITED STATES PATENT OFFICE.

WILLIAM W. TURNER, OF CHICAGO, ILLINOIS.

DESIGN FOR A ROOF-CAP.

SPECIFICATION forming part of **Design No. 26,226**, dated **October 27, 1896**.

Application filed February 23, 1895. Serial No. 539,489. Term of patent 14 years.

To all whom it may concern:

Be it known that I, WILLIAM W. TURNER, a citizen of the United States, residing at Chicago, county of Cook, State of Illinois, have 5 invented and produced a certain new and original Design for Roofs, (Case C';) and I declare the following to be a full, clear, and exact description of the same, reference being had to the accompanying drawing, which 10 forms a part of this specification.

In the drawing the figure is a perspective view showing my roof-cap.

In carrying out the invention I will first explain that the cap constituting the subject 15 of this design application is employed in connection with a roof-covering.

C represents the cap constituting my in-

vention. This cap C, as will be seen, is tapered from end to end and the wider end is turned down, as at b. This turned-down portion is tapered as it nears each edge of the cap, so that the design constituting my invention is a cap convex transversely of its length, tapered from end to end and having the wide end turned down to form a ridge. 20 25

What I claim is—

The design for a roof-cap substantially as herein shown and described.

In testimony whereof I sign this specification in the presence of two witnesses.

WILLIAM W. TURNER.
